(57) **CLAIM**

The ornamental design for a dimmable high bay light, as shown and described.

DESCRIPTION

FIG. 1 is a perspective view of a dimmable high bay light; FIG. 2 is a front view of the dimmable high bay light; FIG. 3 is a back view of the dimmable high bay light; FIG. 4 is a bottom view of the dimmable high bay light; FIG. 5 is a top view of the dimmable high bay light; FIG. 6 is a right side view of the dimmable high bay light; and, FIG. 7 is a left side view of the dimmable high bay light. The broken lines shown in the drawings illustrate portions of the dimmable high bay light that form no part of the claimed design.
